PRESS UNLOADER

Harry M. Ashton, Birmingham, Mich., assignor to Ashton Automation International, Inc., Detroit, Mich., a corporation of Michigan

Filed June 4, 1965, Ser. No. 461,488
3 Claims. (Cl. 214—1)

This invention relates generally to work stock handling apparatus and, more particularly, to a new and improved apparatus for removing or unloading successive workpieces from a work stock forming press such as a punch press, stamping press, or the like.

It is a general object of the present invention to provide a new and improved press unloader which is characterized by constructional and operational simplicity.

It is another object of the present invention to provide a new and improved press unloader of the above character of an extremely compact design and which is easy to assemble and economical to commercially manufacture.

It is still another object of the present invention to provide a new and improved press unloader of an extremely rugged and durable construction and which may be readily adjusted to accommodate presses of varying types and configuration, whereby successive workpieces may be removed from the press without any interference between the various fixed portions of the press and the workpieces.

It is yet another object of the present invention to provide a new and improved unloading press of the above character which is completely automatic in operation.

The foregoing and other objects and advantages of the present invention are achieved through the provision of a novel press unloader that comprises an elongated unloading arm which is mounted so as to be movable from a position adjacent the work stock removing throat or cavity of a conventional punch press, stamping press or the like, to a position spaced away from the press, whereby to remove successive workpieces from the press. The aforesaid unloading arm is provided with guide means for controlling the movement thereof, which means is adjustable in a manner such that the path which the workpieces are traversed along may be varied to accommodate various installation conditions and presses of various types and configurations. A particular feature of the present invention resides in the fact that the path which the successive workpieces traverse lies entirely above the level at which workpieces are initially engaged within the press, thereby permitting the workpieces to be removed from the press without any interference with any of the fixed portions of the press, such as fixedly mounted dies or the like. The unloading arm is provided with means adapted to automatically grip the successive workpieces when engaged therewith, which means is also adapted to automatically release the workpieces after they have been traversed along the aforesaid preselected path, whereby the workpieces may be conveyed to an associated process line, tote box, bin or similar means for transporting them to another work station or the like. The press unloader of the present invention is characterized by extreme simplicity in construction and operation and is therefore easy to install, operate and maintain.

A more complete understanding of the press unloader of the present invention and other features thereof will become apparent from the following detailed description taken in conjunction with the accompanying drawings, wherein:

FIGURE 1 is a side elevational view, partially broken away, of an exemplary embodiment of the press unloader of the present invention;

FIGURE 2 is an enlarged transverse cross sectional view taken along the line 2—2 of FIGURE 1, and

2

FIGURE 3 is an enlarged transverse cross sectional view of the press unloader illustrated in FIGURE 1, taken along the line 3—3 thereof.

Referring now to the drawings, a press unloader, generally designated by the numeral 10 and constructed in accordance with an exemplary embodiment of the present invention, is shown as comprising an elongated unloading arm 12 which comprises upper and lower end sections 14 and 16, the former of which is movably secured between a pair of vertically extending, spaced parallel side plates or members 18 and 20 in a manner such that the lower end section 16 of the arm 12 may be biased to and from a position adjacent the work stock removing throat or cavity of a conventional punch press, stamping press or the like, to effect removal of successive workpieces from the press subsequent to a punching, stamping or other operation which the workpieces have been subjected to, as will later be described.

As best seen in FIGURE 1, the side members 18 and 20 are of identical conformation and are defined by parallel vertically extending forward and rear edges 22 and 24, downwardly inclined lower edges 26, horizontally extending upper edges 28 and upwardly and rearwardly inclined front edges 30. The side members 18 and 20 are secured to each other at their upper and forward edges 28 and 22, respectively, by means of a pair of generally T-shaped spacer members 32 and 34 which extend laterally between the mutually confronting sides of the members 18 and 20, the spacers 32 and 34 being rigidly secured to the members 18 and 20 as by welding or the like. Another spacer bar 36 extends laterally between and is rigidly secured by welding or the like to the confronting sides of the side members 18 and 20 adjacent the rear edges 24 thereof.

The upper end section 14 of the unloading arm 12 is preferably constructed of flat elongated and uniformly thick metal stock and is movably supported between the side members 18 and 20 by means of two pairs of rollers 38 and 40 that are mounted on the opposite sides of the upper end section 14 and are rotatably or slidably disposed within a pair of guide channel assemblies 42 and 44 that are mounted on the inboard sides of the side members 18 and 20, as will be described. As best seen in FIGURE 3, the pair of rollers 38 are mounted on the opposite ends of a cylindrical shaft 46 which extends laterally through a central opening 48 that is formed near the top of the upper end section 14 and is rotatably supported by a pair of antifriction sleeve bearings or bushings 50 and 52 that are secured as by welding or the like to the opposite sides of the section 14. The rollers 38 are slidably disposed within the guide channel assembly 42 which comprises a pair of identical channel members 54 and 56, each of which consists of a backing plate 58 and a pair of spaced parallel guideways 60 and 62. The channel members 54 and 56 are secured to the inboard sides of the side members 18 and 20 in lateral and vertical alignment with one another by means of a plurality of suitable screws, bolts or the like 64. The guideways 60 and 62 of each of the channel members 54 and 56 are spaced apart a distance slightly larger than the diameter of the rollers 38 such that when the rollers 38 are disposed between the guideways 60 and 62, as illustrated in FIGURE 3, the upper end of the unloading arm 12 will be vertically slidably therewithin, as will be apparent.

The pair of rollers 40 are operatively mounted adjacent the lower end of the upper end section 14 of the unloading arm 12 in substantially the same manner as the rollers 38 are mounted on the upper end of the section 14. In particular, the rollers 40 are mounted on the opposite ends of a laterally extending shaft 66 which is rotatably supported by a pair of antifriction bearings or bushings

68 and 70 that are similar to the aforementioned bushings 50, 52 and are secured as by welding to the opposite sides of the arm 12. The rollers 40 are slidably disposed within the guide channel assembly 44 which comprises a pair of identical channel members 72 and 74, each consisting of a backing plate 76 and a pair of spaced parallel guideways, generally designated by the numeral 78. The channel members 72 and 74 are substantially identical in construction to the analogous members 54 and 56 of the assembly 42, with the exception that the guideways 78 of each of the members 72, 74 is rigidly secured to its associated backing plate 76, as by suitable screws, bolts or the like (not shown) and that the backing plates 76 are movably or adjustably secured to the inboard sides of the side members 18 and 20. More particularly, the lower and rearward ends of the channel members 72 and 74 are pivotably secured to the inboard sides of the members 18 and 20, respectively, by suitable bolts, pivot pins or the like (not shown). Accordingly, the upper and forwardmost ends of the channel members 72, 74 are free to pivot to the positions shown in phantom lines in FIGURE 1 about a common laterally extending axis extending through the lower ends of the channel members 72 and 74. The forward ends of the channel members 72, 74 are adapted to be adjustably secured to the side members 18 and 20 in any one of various positions shown by means of suitable screws, bolts or the like (not shown), which extend transversely through suitable openings in the members 72, 74 and through the various series of openings 80, formed in the side members 18 and 20 and thereby function to selectively control the operational movement of the unloading arm 12, as will later be described.

Means for selectively biasing the unloading arm 12 between its various operative positions is achieved by a piston and cylinder assembly, generally designated 82, which is of a conventional design and comprises a cylinder 84 within which the upper end of an elongated piston rod 86 is reciprocably mounted. The assembly 82 is preferably pneumatically actuated and is supplied with pressurized air from a suitable source as is commonly available in factories and the like. The assembly 82 is pivotably mounted on the press unloader 10 by means of a pair of pivot pins, bolts or the like, generally designated 88, as seen in FIGURES 1 and 2. The pivot pins 88 extend transversely inward from the inboard sides of the side members 18 and 20 at the forward edges 22 thereof. As seen in FIGURE 2, suitable sleeves or collars, generally designated 90, are provided on the pins 88 between the opposite sides of the cylinder 84 and the inboard sides of the side members 18 and 20 to limit any lateral or transverse movement of the piston and cylinder assembly 82 relative to the members 18 and 20. As seen in FIGURES 1 and 2, the lower end of the piston rod 86 is pivotably connected to the forward edge of the unloading arm's upper end section 14 by means of a conventional bifurcated clevis member 92 which is threadably or similarly attached to the end of the rod 86 and is pivotably connected to the end section 14 by a suitable pivot pin or the like 94. Accordingly, upon actuation of the piston and cylinder assembly 82, the piston rod 86 will move axially toward the cylinder 84, pivoting the lower end of the unloading arm 12 upwardly along a preselected path, as will later be described.

An elongated generally C-shaped guard 96 extends around the forwardmost and upper end of the piston and cylinder assembly 82, as best seen in FIGURE 1. The guard 96 comprises a pair of spaced parallel side portions 98 which are interconnected at their forwardmost ends by a transversely extending web portion 100, the guard 96 being rigidly secured to the press unloader 10 by having the lowermost ends of the side portions 98 rigidly secured as by welding or the like, to the side members 18 and 20 adjacent the edge portions 30 thereof. The guard 96 prevents work stock being transported in the

vicinity of the unloader 10 from inadvertently engaging and possibly damaging the piston and cylinder assembly 82, as will be apparent.

The lower end section 16 of the unloading arm 12 is generally tubular in cross section and is secured at its upper end to the lower end of the upper section 14 by a suitable screw, bolt, or the like, 102. The lower end section 16 is provided with a work stock engaging jaw assembly, generally designated 104 that is of a conventional design and comprises interengageable jaws 106 and 108 which, when appropriately engaged with an edge portion of a workpiece, will be automatically cammed to the closed position illustrated by the dotted lines in FIGURE 1. The jaw assembly 104 also comprises a piston and cylinder assembly 110 which is preferably pneumatically energized and is adapted to be actuated to selectively advance and retract the jaws 106, 108 to and from the position illustrated in dotted lines where the jaws 106, 108 engage the edge of a workpiece in a manner well known in the art.

The jaw assembly 104 is mounted on the lower end of a cylindrical adjustment rod or shaft 112 which is telescopically mounted within the lower end of the tubular end section 16 of the unloading arm 12. The shaft 112 is provided with a rack 114 that is adapted to cooperate with a spur gear 116 in the conventional manner for varying the axial position of the assembly 104 relative to the lower end of the unloader arm 12. A suitable handle 118 is provided on the gear 116 to facilitate rotating the gear 116 and adjusting the axial position of the shaft 112 and assembly 104 relative to the arm 12.

The press unloader 10 of the present invention is adapted to be detachably secured to the stamping press or the like with which it is operatively associated by means of a pair of generally inverted hook-shaped members, generally designated 120, which have their forward edges secured as by welding or the like to the outboard sides of the side members 18 and 20 adjacent the rear edges 24 thereof. The members 120 are adapted to be hooked over the upper edge of the crown of the press, generally designated by the numeral 122. A bearing plate 124 may be secured, as by welding or the like to the lower end of the crown 122 for engagement with the transversely extending spacer bar 36, whereby the unloader 10 is operatively maintained in the substantially vertical orientation illustrated in FIGURE 1.

Assuming that the jaw assembly 104 has been adjusted to a preselected longitudinal position along the unloading arm 12, an exemplary operational cycle of the press unloader 10 of the present invention is initiated upon energizing the piston and cylinder assembly 110, whereby the jaw assembly 104 will advance to the position indicated by the dotted lines in FIGURE 1. As the assembly 104 advances, the jaws 106, 108 are cammed closed upon engaging an edge portion of the workpiece which has been previously subjected to a stamping, punching or similar operation within the press. At such time as the jaws 106, 108 are tightly engaged with the workpiece, the piston and cylinder assembly 82 may be energized, for example, upon actuation of suitable automatic controls or by actuating suitable manual controls on an associated control panel or the like. Upon energization of the assembly 82, the piston rod 86 will move axially toward the cylinder 84, thereby biasing the lower end of the unloading arm 12 upwardly and forwardly away from the press. As the lower end of the arm 12 moves upwardly, the pair of rollers 40 slide upwardly and forwardly within the channel members 72, 74 and simultaneously, the pair of rollers 38 slide upwardly within the channel members 54, 56. It will be seen that the arm 12 is movably supported within the channel assemblies 42, 44 and by the piston and cylinder assembly 82 such that the lower end thereof moves along a path which is always spaced vertically above the immovable bed or fixed die of the press, thus preventing any interference between the press and

the work stock being unloaded therefrom. At such time as the lower end of the arm 12 reaches a predetermined position, for example, the position indicated by the phantom lines in FIGURE 1, the jaws 106, 108 will release the workpiece, which workpiece may then be transported to a suitable conveyor line, tote box, bin, or equivalent receptacle for transporting the workpiece to another work station or the like. After the jaws 106, 108 have been released, the piston and cylinder assembly 82 may be de-energized, thereby permitting the lower end of the unloading arm 12 to be pivoted downwardly and rearwardly to the position indicated by the solid lines in FIGURE 1. As the arm 12 is thus traversed to the aforesaid position, the piston and cylinder assembly 110 is deenergized, thereby retracting the jaw assembly to its position indicated by the solid lines in FIGURE 1, thus completing the operational cycle of the unloader 10 and preparing the various component members thereof for the next successive cycle, as above described.

It will be seen from the foregoing description that the present invention provides a novel press unloader of an extremely simple design which is therefore easy to assemble and economical to commercially manufacture. A particular feature of the present invention resides in the fact that the channel assembly 44 may be easily adjusted to vary the paths which the lower end of the unloading arm 12 follows as it is biased away from the associated press by the piston and cylinder assembly 82, whereby to accommodate different presses and, more particularly, dies of different types and configurations, thus permitting the unloader 10 to remove successive workpieces from a wide variety of different types of presses without any interference between the presses and the various workpieces being unloaded therefrom. Another feature of the press unloader 10 of the present invention resides in the fact that it is relatively small in the lateral dimension, thereby enabling it to be operatively installed in a minimum amount of space. Still another feature of the present invention will be seen from the fact that the press unloader 10 comprises very few moving parts, thereby minimizing component replacement and maintenance time and accompanying expense to a minimum.

While it will be apparent that the exemplary embodiment herein illustrated is well calculated to fulfill the objects above stated, it will be appreciated that the press unloader 10 of the present invention is susceptible to modification, variation and change without departing from the proper scope or fair meaning of the subjoined claims.

What is claimed is:

1. In a press unloader, a pair of vertically extending

spaced parallel side members, an elongated unloading arm disposed between said side members and comprising upper and lower end sections, first and second guide channel assemblies disposed between said side members, each of said assemblies comprising a pair of channel members secured one to the inboard side of each of said side members, each of said channel members comprising a backing plate and spaced parallel guideways, the channel members of said first assembly being laterally aligned and extending vertically along said side members, the channel members of said second assembly being laterally aligned and extending forwardly and upwardly along said side members, a first pair of rollers journal supported on the upper end of said upper section of said arm and slidably disposed within said first channel assembly, a second pair of rollers journal supported on the lower end of said upper section of said arm and slidably disposed within said second channel assembly, a piston and cylinder assembly comprising a reciprocable piston rod, said 10 last mentioned assembly being pivotally connected between said side members adjacent the forward edges thereof, said piston rod being pivotally connected to said arm whereby actuation of the said last mentioned assembly biases the lower end of said arm along a preselected path 15 from a first position adjacent the press to a second position spaced away from the press, and clamping means secured to the lower end of said arm detachably engageable with work stock within the press.

2. The invention as set forth in claim 1 wherein one 20 of said guide channel assemblies is adjustably secured to said side members for varying the position of said path relative to the press.

3. The invention as set forth in claim 1 wherein said path lies entirely above the lower end of said arm when 25 said arm is disposed in said position adjacent the press.
